US0D1068800S

(12) **United States Design Patent** (10) **Patent No.:** **US D1,068,800 S**
(45) **Date of Patent:** **** Apr. 1, 2025**

(54) **DISPLAY SCREEN WITH GRAPHICAL USER INTERFACE OF A GAMING MACHINE**

(71) Applicant: **LNW Gaming, Inc.**, Las Vegas, NV (US)

(72) Inventors: **Luisa Leal**, Henderson, NV (US); **Kenneth Shawn Soong**, Henderson, NV (US)

(73) Assignee: **LNW Gaming, Inc.**, Las Vegas, NV (US)

(**) Term: **15 Years**

(21) Appl. No.: **29/871,833**

(22) Filed: **Feb. 28, 2023**

(51) LOC (15) Cl. **14-04**

(52) U.S. Cl.

USPC **D14/488**

(58) **Field of Classification Search**
